MACHINE FOR PRODUCING SPACED GROUPS OF TUFTS ON FABRIC

Robert H. Bradwell, Sumter, S. C., assignor to
 Polly Prentiss, Inc., Sumter, S. C., a corpora-
 tion of South Carolina

Application June 3, 1936, Serial No. 83,400

11 Claims. (CL 112—79)

My invention relates to a machine for pro-
 ducing spaced groups of tufts on fabric.

An important object of the invention is to
 provide a machine of the above mentioned char-
 acter which will form the spaced groups of tufts
 without producing connecting loops between
 them.

A further object of the invention is to provide
 means for producing the spaced groups of tufts,
 the tufts in the groups being substantially uni-
 form in length, thereby eliminating the necessity
 of cutting or trimming the tufts.

A further object of the invention is to provide
 a machine of the above mentioned character
 which will operate continuously and is wholly
 automatic in operation.

Other objects and advantages of the invention
 will be apparent during the course of the follow-
 ing description.

20 In the accompanying drawings forming a part
 of this application and in which like numerals
 are employed to designate like parts throughout
 the same,

25 Figure 1 is a side elevation of a machine em-
 bodying my invention,

Figure 2 is an end elevation of the same with
 the head plate removed,

Figure 3 is a perspective view of the operating
 parts of the machine,

30 Figure 4 is an exploded perspective view of the
 hook and associated elements,

Figure 5 is a side elevation of the needle show-
 ing the same in the raised starting position,

Figure 6 is a similar view showing the needle
 35 moved to the lowermost position on the down
 stroke,

Figure 7 is a similar view showing the hook
 engaging within the loop before the needle starts
 on the up stroke, with the free end of the yarn
 held in the fabric,

Figure 8 shows the needle in the elevated posi-
 tion at the completion of its cycle, with the free
 end of the yarn pulled from the fabric,

Figure 9 is a similar view showing the needle
 45 on the down stroke to produce the next loop,

Figure 10 shows the hook engaging within the
 loop and the needle returning to the upper posi-
 tion,

Figure 11 shows the needle in the elevated posi-
 50 tion at the end of the second cycle with the loop
 on the rear end of the hook, but not cut,

Figure 12 shows a plurality of formed loops,
 with the needle in the raised position, all of the
 loops being cut except the last loop,

55 Figure 13 shows the needle locked in the raised

position and the work fed forward for one stitch
 so that the last loop is cut.

Figure 14 shows the work fed for another
 stitch and the cut yarn from the needle being
 withdrawn from the fabric by the feeding action 5
 of the fabric, and

Figure 15 is a perspective view of the fabric
 and spaced groups of tufts.

In the drawings, wherein for the purpose of
 illustration is shown a preferred embodiment of 10
 my invention, the numeral 20 designates a sew-
 ing machine, as a whole, of any well known or
 preferred type, such as the ordinary Singer sew-
 ing machine, as shown in my Patent 2,038,923.
 This sewing machine comprises a stock 21, an 15
 arm 22, and a head 23. The usual head plate 23'
 has been removed in Figure 2. The stock 21 is
 mounted upon the flat base 24. The head 23 is
 provided with the usual vertical reciprocating
 needle bar 25, carrying a needle 26, which is 20
 rigidly clamped thereto, for permanent move-
 ment therewith. This needle has the usual eye
 for receiving the tufting thread or yarn 27. This
 tufting thread is passed through guides 28 and
 a tension device 29. The tension device is so 25
 adjusted that it is loose and will offer no tension
 or resistance upon the thread, but simply serves
 as a guide. The tufting thread or yarn is fed
 from the usual cone spool. In the present in-
 vention, the machine embodies the usual driving 30
 shaft 30, driven by a grooved pulley 31, or the
 like. At its forward end, the driving shaft 30
 is provided with a crank-disk 32 rigidly secured
 thereto, and having pivotal connection with a
 link 33. This link 33 is pivotally connected with 35
 a sleeve 34. The sleeve 34 is part of the original
 sewing machine and on the original sewing ma-
 chine, this sleeve is clamped to the needle bar
 25, to reciprocate it, by means of a set screw.
 In accordance with my invention this set screw 40
 is removed and the sleeve 34 is therefore slid-
 ably mounted upon the needle bar 25. This sleeve
 is capable of raising the needle bar, but the
 needle bar may be held in the raised position
 when the sleeve 34 is lowered, as will be ex-
 plained. Arranged above the sleeve 34 is a 45
 ring 35, rigidly clamped to the needle bar 25, and
 this ring is engaged by a compressible coil spring
 36, surrounding the needle bar, engaging the
 ring 35 and the end wall 37 of the head 23, as 50
 shown. The spring 36 serves to move the needle
 bar downwardly while the sleeve 34 raises the
 needle bar upwardly, but the needle bar is per-
 manently slideable within the sleeve 34.

The sewing machine embodies the usual presser 55

foot 38, carried by a reciprocating presser bar 39, which may be raised by a finger engaging lever 40, or by any other desirable means. The sewing machine further comprises the work feeding means, to advance the work from the operator, in a stitch-by-stitch manner, including dogs 41, operating through a suitable opening in the base plate 24, and these dogs are rigidly mounted upon a rigid dog support link or bar 42. At one end, the link 42 is rigidly connected with a head 43, pivotally connected at 44 with generally vertical cranks 45, in turn rigidly mounted upon a rock shaft 46 extending longitudinally of and beneath the base 24, and held by suitable stationary bearings. At its opposite end, the link 42 is provided with a fork 47, receiving a roller 48, pivotally mounted upon a generally horizontal crank 49, in turn rigidly mounted upon a rock shaft 50. This rock shaft is arranged beneath the base 24 and extends longitudinally thereof in spaced parallel relation to the rock shaft 46, and is supported by stationary bearings. These rock shafts are driven from the driving shaft 30, as is well known in the art. The arrangement of the rock shafts 43 and 50 correspond to the arrangement of the rock shafts 27 and 33, in my said Patent 2,038,923. It might be stated at this point that the movement of the rock shaft 46 moves the dog carrying link 42 longitudinally, while the movement of the rock shaft 50 serves to raise and lower this link. When the link 42 is moved longitudinally in a forward feeding direction, the crank 49 raises the same to feed the fabric and when the link 42 is moved rearwardly in a longitudinal direction, the crank 49 lowers the link 42, thus releasing the work so that it is held in the new position by the presser foot. The foregoing description of the feeding mechanism is that of the ordinary sewing machine, such as the Singer sewing machine, shown in my Patent 2,038,923.

Means are provided to hold or lock the needle bar in the raised position, comprising a horizontal shaft 51, one end of which is journaled in a stationary bearing 52 and its opposite end in a bearing 53, carried by a stationary arm 54. This stationary arm has an opening formed in its lower end to receive the exterior of a bearing element 55, and the arm is clamped to this bearing element by a set screw 56, or the like. The driving shaft 30 is equipped with a small gear or pinion 57, rigidly mounted thereon, engaging a larger gear 58, in turn rotatably mounted upon a stub shaft 59, supported by the arm 54. Preferably formed integral with the large gear 58, for rotation therewith, is a small gear 60, engaging a larger gear 61, rigidly mounted upon the shaft 51. The gear ratio between the shafts 30 and 51 is preferably such that the shaft 51 is turned for one complete revolution when the shaft 30 has made fourteen complete revolutions. Of course the invention is not necessarily restricted to this gear ratio. Rigidly connected with the forward end of the shaft 51 is a mutilated disk or element 62, which has a circularly curved edge 63, extending throughout 9/14 of the circle, the cut away portion representing the remaining 5/14 portion of the complete circle. The circularly curved portion 63 extends from the point 64 to the point 65. The disk 62 includes a hook portion 66, having a generally circumferentially extending recess 64'. From the point 64, the disk 62 has a straight generally radial shoulder 67. Adapted

to coact with the disk 62 is a roller 68, rotatably mounted upon a block 69, which is rigidly clamped to the upper portion of the needle bar, and this block operates within a stationary vertical guide 70. It might be stated at this point 5 that when the roller 69 engages the circularly curved face 63 of the disk 62, that the needle bar is held or locked in the raised position, and when the roller trips off of the point 64, the needle bar is free to reciprocate for its entire 10 stroke, until again picked up by the point 65 of the hook 66. The recess 64' is provided so that the roller 68 may move therein during the reciprocation of the needle bar, so that the reciprocating movement will not be interfered with 15 until the point 65 picks up the roller 68. The downward movement of the needle bar is limited by the position of the sleeve 34 and the lower end of the guide 70. The disk 62 turns in the direction of the arrow and when point 65 reaches 20 the raised position, roller 68 is elevated, so that point 65 passes beneath the roller.

Means are arranged beneath the base 24 for coaction with the needle, for holding and cutting the loops to produce the tufts. This means comprises a stationary arm or bracket 71, upon which is suitably pivoted at 72, a vertically swinging arm 73 arranged to swing parallel with the feeding movement of the work. This arm is arranged near and upon one side of the needle, and carries a generally horizontal hook or looper 74, rigidly connected therewith. This hook or looper has a down turned bill 75', and the hook or looper moves across the path of travel of the needle, upon one side of the needle, to enter the formed 35 loop, and to hold the loop against upward movement when the needle rises. The hook or looper 74 is directly mounted upon a head or plate 75, which is rigidly attached to the swinging arm 73. A vertically movable reciprocatory 40 blade 76 is slidably mounted within a groove 71, formed in the head 75, and this blade has an inclined cutting edge 78 at its top to coact with the longitudinal edge of the hook 74, to cut the loop or loops accumulated thereon. The arrangement and operation of the blade and hook are somewhat similar to the corresponding arrangement in my Patent 2,038,923. When the needle descends and at about the time the same starts to rise, the hook moves forward to enter 50 the loop. When the needle rises, the hook moves rearwardly, and the blade 76 rises to cut the loop. The blade 76 is so adjusted that the last loop remains unsevered on the hook, when the needle rises. The operating means for the blade 55 50 comprises a lever 78', having a forked end which straddles the swinging arm 73, and is pivoted thereto at 79. The sides 80 of the forked lever are in turn forked to provide notches 81, receiving rollers 82, pivoted upon the lower end of the 60 reciprocating blade 76. The lever 78' is bent or extended downwardly and its free end engages a stiff leaf spring 83, which is attached to the arm 73, at 84. The spring 83 acts upon the lever 78 to raise its free end, whereby its forked end 65 is moved downwardly and the blade 76 lowered. The lever 78' is moved in an opposite direction to raise the blade, by a crank 85, depending from the rock shaft 46, and engaging a relatively 70 large flat head 86, carried by a bolt 87 adjustably mounted upon the lever 78' and adapted to be locked in adjustment by a nut 88. The pivoted arm 73 carries a roller 89, operating within a fork 90, depending from and rigidly secured to the dog carrying link 42. The pivoted arm 78 75

is swung by the movement of the link 42, although it may be swung by other means.

The operation of the machine is as follows:

The fabric is arranged beneath the presser foot 38 in the usual manner and is fed from the operator by the action of the feed dog 41. The fabric is fed a distance of one stitch upon each cycle of operation of the needle. The tufting yarn or thread 27 runs free or without tension. This is important in the operation of the machine, for if tension is applied to the tufting thread or yarn, the thread would be pulled from the eye of the needle, when the needle descended. Where the tufting yarn or thread is fed without tension, there is sufficient frictional engagement between this thread or yarn and the wall of the eye of the needle so that the tufting thread is not pulled out of the same. In the starting of the operation, the needle 26 is in the raised position, Figure 1, and the roller 68 is engaging the circularly curved edge face 63, adjacent to the point 64. The disk 62 is travelling in the direction of the arrow, Figure 2, and when the roller 68 passes off the point 64, it does not immediately descend, as the link 33 is then in the raised position, but the further turning movement of the driving shaft 30 lowers the link 33 and the spring 36 then causes the needle bar and needle to travel downwardly. The needle is shown in the raised starting position in Figure 5, and at the end of the lowered position in Figure 6. When the needle has reached the lowered position, the tufting thread or yarn 27 has been forced through the fabric, producing a loop 91 upon the lower side of the fabric 92. This loop includes a leading side 93 and a trailing side 94, the work being fed in the direction of the arrow. The free end of the leading side 93 is held within the fabric 92, as shown in Figures 6 and 7. At about the time that the needle 26 reaches the lowermost position, the hook 14 moves across the path of travel of the needle and enters the loop to receive the same thereon. This is shown in Figure 7. The needle 26 now moves upwardly until it again assumes the uppermost position, Figure 8, and the first cycle of operation of the needle is completed. When the needle moves upwardly, the hook 14 engaging the loop 91, exerts a pull upon the loop and the free end of the leading side 93 of the loop is pulled out of the fabric 92, and the thread pulled upwardly to a certain extent with the needle, the needle slipping on the thread to a certain extent. As a result of this action, there is left only one strand which may be designated by 53 the numeral 94', and this strand will be of substantially the same length of the succeeding loops to be produced, Figure 8. The strand 94' will pass off of the hook 14 and there will be no cutting action. The first cycle of operation of the 60 needle being completed, the second cycle is started and the needle moves downwardly and forces the thread through the fabric, Figure 9, to produce the loop 91a, and about the time the needle reaches the lowermost position, the hook 14 enters the loop to receive the loop thereon, Figures 9 and 10. The needle then moves upwardly and the second cycle is completed, Figure 11. The loop 91a remains on the hook, but is not cut when the blade 76 moves upwardly upon this cycle. 65 The needle now moves downwardly to produce another loop which is caught on the hook and retained thereon as the needle moves upwardly to complete the third cycle of operation, and the work is fed forwardly another stitch. This feeding movement of the work now brings the loop 91a

into the contracted portion of the cutter and the upward movement of the blade 76 will now cut the loop 91a, but the loop 91b is not cut, the last loop remaining uncut on the hook. The needle now starts on its downward stroke and produces a loop 91c, which is caught on the hook and the needle travels upwardly to complete the fourth cycle, and the loop 91b is fed forward another stitch and is cut by the blade upon the upward movement of the needle, while loop 91c is not cut. 10 The needle now moves downwardly and produces a loop 91d which is caught on the hook and the needle moves upwardly to complete the fifth cycle, and is then locked in the raised position as the roller 68 will be caught on the point 65 and 15 will now engage the circularly curved edge surface 63. When the needle moved up to complete the fifth cycle, the work was advanced another stitch and loop 91c cut, while loop 91d remained uncut. The machine continues to operate, and 20 the link 33 will move up and down to complete nine cycles while the needle bar and needle are stationary. Upon the completion of the first cycle of the link 33, with the needle raised and stationary, the work has been advanced to the 25 position shown in Figure 13 and the blade has cut the loop 91d. This leaves the trailing side 91e in the fabric, and as the work continues to feed, the side 91e is pulled out of the fabric and before or at the time that the link 33 has completed its 30 last of the nine cycles, and side 91e is out of the fabric and the needle and arm assume the position shown in Figure 5, whereby the entire cycle of operation has been completed. The further operation of the machine will again produce five 35 cycles of the operation of the needle to produce the loops, as explained. It is thus seen that spaced groups of loops are produced, and the loops in each group are cut to produce the tufts. Spaced groups of tufts are thus produced. In 40 producing the spaced groups of loops, there are four of the loops finally left in each group, the closed ends 91f appearing on the top of the fabric, as passed through the machine. Particular attention is called to the fact that there is no connecting yarn or loops spanning the spaces between the spaced groups of loops, as the yarn is pulled out of the fabric at the beginning and at the end of the formation of each group of loops.

It is to be understood that the form of my invention herewith shown and described is to be taken as a preferred example of the same and that various changes in the shape, size and arrangement of parts may be resorted to, and that the order of the steps of the method may be 45 changed, without departing from the spirit of my invention or the scope of the subjoined claims.

Having thus described my invention, I claim:

1. In a machine for producing tufts upon a fabric, a reciprocating needle bar, a needle carried thereby to force the thread through the fabric and produce loops, a looper movable across the path of travel of the needle bar to receive the loops thereon, means to cut the loops upon the looper, a spring to move the needle bar downwardly, a sleeve slidably mounted upon the needle bar and serving to raise the needle bar, means to reciprocate the sleeve, a holding element connected with the needle bar, a rotatable disk for coaction with the holding element and having a 50 part to engage with the holding element for retaining the needle bar raised and a cut away part to permit of the downward movement of the needle, means to rotate the disk, and work feeding means to advance the fabric. 55

2. In a machine for producing tufts upon a fabric, a reciprocating needle bar, a needle carried thereby to force the thread through the fabric and produce loops, a looper movable across the path of travel of the needle bar to receive the loops thereon, means to cut the loops upon the looper, a spring to move the needle bar downwardly, a sleeve slidably mounted upon the needle bar and serving to raise the needle bar, a driving shaft, means operated by the driving shaft to reciprocate the sleeve, a rotatable disk arranged near the needle bar and having a circularly curved face and a cut away portion, a holding element secured to the needle bar and adapted to engage said face, means to rotate the disk, and work feeding means to advance the fabric.
3. In a tufting machine, a reciprocating needle, a looper movable across the path of travel of the needle, a reciprocating blade to travel with the looper in one direction and movable toward and from the looper, a pivoted lever connected with the blade to reciprocate the same, a movable member to positively depress one end of the lever, and a spring to raise such end of the lever.
4. In a tufting machine, a reciprocating needle, a swinging arm, a looper carried by the swinging arm to move across the path of travel of the needle, a movable blade shiftable toward and from the looper, a lever pivoted upon the arm and connected with the blade, a spring to move the lever in one direction, and means to positively move the lever in the opposite direction.
5. In a tufting machine, a generally vertical reciprocating needle bar, a needle carried thereby, a generally horizontal driving shaft, means connected with the driving shaft and capable of raising the needle bar, means to lower the needle bar, a generally horizontal rotatable shaft arranged near the upper end of the needle bar, a control element carried by the generally horizontal rotatable shaft, an element secured to the upper end of the needle bar and engaging and disengaging the control element and serving to hold the needle bar in the raised position when it engages the control element, means coacting with the needle to produce loops, and means to sever the loops to produce tufts.
6. In a tufting machine, a reciprocating needle bar, a needle carried thereby, a driving shaft, an element movable longitudinally of the needle bar and adapted to raise the same, a spring to lower the needle bar, means connecting the movable element with the driving shaft, a rotatable shaft, a control element driven by the rotatable shaft, an element secured to the needle bar to engage and disengage the control element, means to coact with the needle to produce tufts.
7. In a tufting machine, a disk having a circularly curved edge and a circumferentially extending recess, means to rotate the disk, a reciprocating needle bar, a needle carried by the bar, an element carried by the needle bar to engage and disengage the curved edge of the disk, means capable of raising the needle bar, and means to lower the needle bar when the element disengages the disk.
8. A tufting machine for producing spaced tufts upon a fabric, comprising a base, a stock mounted upon the base and carrying an arm, a head carried by the arm, a reciprocating needle bar oper-
- ating within the head and having a needle movable therewith at all times during the movement of the needle bar, a spring surrounding the needle bar within the head and acting against a stationary part of the head and serving to move the needle downwardly, a stop element carried by the needle bar, a collar arranged within the head and slidably mounted upon the needle bar beneath the stop element, work feed means, means to hold the needle bar elevated and against downward movement in opposition to the spring during the operation of the work feed means to feed the work, means to reciprocate the collar, a reciprocating looper to enter the loop produced by the needle, and means to sever the loop.
9. A tufting machine for producing spaced tufts upon a fabric, a base, a stock mounted upon the base and carrying an arm, a head carried by the arm, a reciprocating needle bar operating within the head, a needle secured to the needle bar to reciprocate therewith, a spring serving to move the needle bar downwardly and acting against a stationary part of the head, a stop element carried by the needle bar, a collar slidably mounted upon the needle bar beneath the stop element, work feed means, means to hold the needle bar in the raised position with the needle out of contact with the fabric and against the action of the spring and during the operation of the work feed means to feed the work, a reciprocating looper to enter the loop produced by the needle, and means to sever the loop.
10. A tufting machine for producing spaced tufts upon a fabric, a support, a reciprocating needle bar carried by the support, a needle secured to the needle bar to reciprocate therewith at all times during the sewing action, a spring serving to move the needle bar downwardly and engaging a stationary part of the support, a stop element carried by the needle bar, a collar slidably mounted upon the needle bar beneath the stop element, work feed means, means to hold the needle bar in the raised position with the needle out of contact with the fabric and against the action of the spring, means to reciprocate the collar, a reciprocating looper to enter the loop formed by the needle, and means to sever the loop.
11. A tufting machine for producing spaced tufts upon a fabric, a base, a stock mounted upon the base and having an arm, a hollow head carried by the arm, a reciprocating needle bar operating within the hollow head, a needle secured to the needle bar, a ring arranged within the hollow head and clamped to the needle bar, a compressible coil spring surrounding the needle bar within the head and engaging at its lower end with the ring and at its upper end with the head, a sleeve arranged within the hollow head and slidably mounted upon the needle bar and adapted to engage with the ring to raise the needle bar, a drive shaft carried by the arm, a crank disc carried by the drive shaft, a link connecting the crank disc and sleeve, means to hold the needle bar raised during the operation of the work feed means to feed the work, a reciprocating looper to enter the loop formed by the needle, and means to sever the loop.
